SPARK PLUG GAP SETTER

Michael A. Bretsch and Robert K. Christie, Toledo, Ohio, assignors to Champion Spark Plug Company, Toledo, Ohio, a corporation of Delaware

Application May 21, 1949, Serial No. 94,658

1 Claim. (Cl. 153—39)

1
This invention relates to means for setting the gaps of spark plug electrodes, and particularly ground electrodes of the multiple prong type commonly used in aviation spark plugs.

An object of the invention is the provision of a simple and efficient means that is easily operable to simultaneously apply a yielding predetermined inward pressure to opposing electrodes to set them in predetermined spaced relation to the common center electrode without danger of cracking the nose portion of the spark plug insulator.

Further objects and advantages of the invention will be apparent from the following description, and from the accompanying drawings illustrating one embodiment of the invention, in which—

Fig. 1 is a side elevation of an apparatus embodying the invention, with a spark plug in gap setting position therein and with the pressure parts in released position; Fig. 2 is a top plan view thereof; Fig. 3 is a section on the line 3—3 of Fig. 2; Fig. 4 is an enlarged plan view of the apparatus, with parts broken away and with the gap setting members in electrode engaging positions; Fig. 5 is a section on the line 5—5 in Fig. 4, and Fig. 6 is a section on the line 6—6 in Fig. 4.

Referring to the drawings, 1 designates a standard for mounting on a work bench, or the like, and secured to the top of this standard by screws 2, or the like, is a top member 3. This member has a short arm 4 projecting upward from the standard and a long arm 5 projecting laterally therefrom. The arm 5 has a vertical opening 6 therethrough that is oblong lengthwise of the arm and in which a spark plug receiving bushing 7 is floatingly mounted. In the present instance, the bushing has its upper end radially flanged to set on the upper marginal edge wall of the opening 6 and is of a diameter to substantially fit the width of the opening 6, so that the bushing may have limited floating movements lengthwise of the arm 5. A split spring ring 8 is seated in an annular recess in the bushing below the arm and coacts with the lower edge wall of the opening to retain the bushing therein.

A spark plug 9 to be adjusted is placed in the bushing 7 with its firing end up and with its shell shoulder 10 seating on an internal flange 11 in the lower end of the bushing. The maximum diameter of the shell is somewhat less than the internal diameter of the bushing to permit an easy sliding of one with the other. The spark plug has the customary center electrode 12 and side or ground electrodes 13. The side electrodes

are of the multiple prong type and, in the present instance, project inwardly from a ring 14 that is fixedly attached to the exposed end of the shell 15 of the plug, as well understood in the art.

5 The side electrodes have their free end portions angled outwardly lengthwise of the plug and terminating in spaced relation to the center electrode. The side electrodes erode in use and thus require adjustment inwardly towards the center electrode to re-establish the proper gap setting.

The outer end of the arm 5 is provided with an upwardly extending fork 16 in which is pivoted a thrust finger 17 for vertical swinging movements and adapted to extend inward from its 15 pivot on a slight downward angle from the horizontal so that its nose may engage in the angle of an adjacent side electrode 13 of a spark plug mounted in the bushing 7. A spring finger 18 bears against the inner end of the thrust finger 17, and when the finger is in elevated position the spring acts to hold it in such position, as shown in Fig. 1.

The inner end portion of the member 3 is vertically slotted at 20 (Fig. 6), and mounted with 25 in such slot on a pivot 21 is a vertically swinging rocker arm 22. This arm extends upward from its pivot a distance above the arm 5 and has a thrust finger 23 projecting inwardly at substantially a right angle thereto from a slot in its outer end. The finger is normally held in the outwardly retracted position shown in Fig. 1 by a coiled expansion spring 24 (Fig. 6). When swung inwardly from such position, the free end of the finger 23 engages the angle of that electrode 13 opposing the one engaged by thrust finger 17.

The means for applying inward movement to the arm 22 comprises a cam 25 that is fixedly mounted on a rock-shaft 26 in the fork of the arm 4 and acts against a roller on the arm 22. 40 The shaft 26 is journaled in the arm 4 and extends a distance from a side of the arm. A block 27 is rotatably mounted on the outer end of this shaft and has a lost motion connection therewith through a pin 28 projecting from the shaft into a segmental slot 29 in the block. A handle or lever arm 30 extends radially from the block. The block and shaft are yieldingly connected by a coiled spring 31, which has engagement at one end with a pin 32 on the block and at its other end with a pin 33 on the shaft. The spring 31 normally holds the block 27 in position for the left hand wall of the slot 29 to engage the pin 28. As indicated in Figs. 1 and 55 3, a swinging of the handle 30 in counterclock-

wise direction will cause the block to turn on the shaft away from the pin 28 and to apply a yielding turning force to the shaft and its cam 25 through the spring 31. The initial movement of the power applying block, and until the torque finger 23 engages the respective electrode 13, is practically unopposed so there is no relative movement of the block 27 on the shaft. The continued movement of the block 27, necessary to cause the opposing fingers 17 and 23 to co-operate to effect the desired gap setting of the opposing electrodes 13, now transmits yielding force to the shaft through the spring 31 due to the lost motion pin-and-slot connection between the block and shaft. Thus, the operator, by watching the movement of the pin 28 within its slot 29, can determine the gap setting pressure applied to the finger 23 and discontinue the movement at the desired point. An index mark on block 27 can be correlated with the position of pin 28 to show when the proper pressure has been applied to the electrode. It is thus possible to obtain a uniform setting of the gaps in successive plugs without danger of applying so much pressure to the electrodes that fracture of the spark plug core might take place.

The width of the spark gap or space between the side and center electrodes is determined by a gauge member 35 that has two laterally spaced gap fingers 36 at its inner end adapted to straddle the center electrode 12 of a spark plug and provide a firm spacing means of predetermined thickness between it and two opposed side electrodes. The operator holds the gauge 35 in position with one hand while using the other hand to operate the handle 30 to apply the desired gap setting torque to the shaft 26 and to the two opposed electrodes 13 engaged by the gauge member.

When the gap has been properly set for two opposed side electrodes 13, the handle 30 is moved in clockwise direction to the position shown in Fig. 1, so that the thrust finger 23 and its carrying arm 22 are retracted to inoperative position by the action of the spring 24. The finger 17 is also raised to the upright position shown in Fig. 1 and the gauge member 35 is removed from engagement with the spark plug. This having been done, the spark plug is turned in the bushing 7 to bring the next pair of side electrodes 13 into line with the gap setting fingers 17 and 23, and the gauge is replaced with its fingers in gap spacing relation between such electrodes and the center electrode. The finger 17 is then turned down into engagement with

its adjacent electrode and the handle 30 operated to position the finger 23 in engagement with the electrode nearest it and to apply the necessary gap setting pressure thereto. This setting pressure is determined by the extent of movement of the pin 28 in the slot 29 and when the pin has assumed a predetermined position in such slot the operator knows that the necessary pressure has been applied. During the positioning of the fingers 17 and 23 in engagement with the electrodes and the application of a gap setting pressure thereto, the spark plug is permitted to freely move transversely with the bushing 7 in the arm opening 6 lengthwise of the arm, thus eliminating all strain from the spark plug tending to crack its insulator.

We wish it understood that our invention is not limited to any specific construction, arrangement or form of the parts, as it is capable of numerous modifications and changes without departing from the spirit of the claim.

Having thus described our invention, what we claim as new, and desired to secure by United States Letters Patent, is:

In an apparatus of the class described, a spark plug holder, means for gauging the spacing between the center and opposed side electrodes of a spark plug in the holder, a pivoted thrust finger mounted for movement into and out of position to engage a side electrode of the spark plug, a pressure applying finger mounted for swinging movements into gap setting engagement with an opposing side electrode of the spark plug, and means operable to apply a predetermined yielding inward gap setting pressure to the swinging pressure finger to apply a gap setting pressure to the engaged electrode in opposition to said thrust finger.
